Primary Examiner — David Muller*Assistant Examiner* — Nathan Johnston(74) *Attorney, Agent, or Firm* — Gardner Groff Greenwald & Villanueva, PC**(57) CLAIM**

The ornamental design for an enteral syringe, substantially as shown and described.

DESCRIPTION

FIG. 1 is a perspective view of an enteral syringe showing our new design.

FIG. 2 is a front elevation view thereof.

FIG. 3 is a rear elevation view thereof.

FIG. 4 is a first side elevation view thereof.

FIG. 5 is a second side elevation view thereof.

FIG. 6 is a first end elevation view thereof; and,

FIG. 7 is a second end elevation view thereof.

The broken lines show portions of the design that form no part of the claimed design.
